COMBINED MIRROR AND STAND

Richard B. Park, West Hartford, Conn., and David Maxwell, New York, N. Y., assignors to The Fuller Brush Company, Hartford, Conn., a corporation of Connecticut

Application November 19, 1953, Serial No. 27,679

Term of patent 14 years

(Cl. D86—10)

To all whom it may concern:

Be it known that we, Richard B. Park and David Maxwell, citizens of the United States, residing respectively at West Hartford, Connecticut, and at New York, New York, have invented a new, original, and ornamental Design for a Combined Mirror and Stand, of which the following is a specification, reference being had to the accompanying drawing, forming part thereof.

Fig. 1 is a front view of a combined mirror and stand showing our new design;

Fig. 2 is a rear view thereof;

Fig. 3 is a side view thereof;

Fig. 4 is a side view similar to Fig. 3 but showing the legs of the stand in different relative positions;

Fig. 5 is a sectional view taken along the line 5—5 of Fig. 4.

We claim:

The ornamental design for a combined mirror and stand, as shown.
